UNITED STATES PATENT OFFICE.

THOMAS JAMES LITTLE, JR., OF WOODBURY, NEW JERSEY, ASSIGNOR TO WELSBACK LIGHT COMPANY, OF GLOUCESTER CITY, NEW JERSEY, A CORPORATION OF NEW JERSEY.

GAS-LIGHTING DEVICE.

1,047,095.

Specification of Letters Patent. Patented Dec. 10, 1912.

Application filed October 20, 1911. Serial No. 655,721.

To all whom it may concern:

Be it known that I, THOMAS J. LITTLE, Jr., a resident of Woodbury, in the county of Gloucester and State of New Jersey, have 5 invented a new and useful Improvement in Gas-Lighting Devices, of which the following is a full, clear, and exact description, reference being had to the accompanying drawings, forming part of this specification, 10 in which—

Figure 1 is a side view showing one form of my invention applied to a gas lamp of the inverted incandescent type with the gas valve in closed position; Fig. 2 is a view 15 partly in elevation and partly in vertical section taken at right angles to Fig. 1, but showing the gas valve in its opened position; Fig. 3 is a detail view showing the holder for the pyrophoric alloy abrader; 20 Fig. 4 is a side view showing another form of my invention applied to a lamp; and Fig. 5 is a detail sectional view of a portion of the device shown in Fig. 4.

My invention has relation to gas-lighting 25 devices adapted for use in connection with gas lamps, gas stoves and, in fact, any type of gas-burning appliance.

My invention relates more particularly to 30 that class of gas-lighting devices which employ a pyrophoric alloy, which has the property of emitting very hot sparks when scratched by a hard substance.

A particular object of my invention is to 35 provide an attachment of this character which, when actuated, will first open the gas valve and will then produce the igniting sparks, and which will compel a pause by the operator between the two operations of sufficient length to insure the gas reaching 40 the igniter at the time the sparks are produced. Prior to my invention, it has been proposed to employ a rotary device for effecting the scratching or abrading of pyrophoric alloy and for the opening of the gas 45 cock, but such a device has not proven satisfactory in operation, because the twisting or turning movement is a very quick one and the sparks are produced before the gas reaches the point of ignition and it is difficult to instruct or accustom the user to hesitate in the middle of the operating movement. If a simple reciprocating movement 50 be used, the same disadvantage exists and such a device is also open to the objection

that there is a sharp, rasping motion of the 55 abrader over the pyrophoric material which results in jarring the gas fixture and the frequent breakage of the fragile mantle when the device is employed in a lighting burner. My invention overcomes these objections by 60 providing a device which requires two separate movements for its operation and which will compel a pause on the part of the operator between such movements. The first movement opens the gas valve, while the 65 second movement scratches the pyrophoric alloy and produces the spark.

In the accompanying drawings, I have 70 shown my invention applied to a lamp of the inverted incandescent type, but as above indicated, my invention is not limited thereto.

In these drawings, the numeral 2 designates the body of the burner having a shade-holding ring 3 and a gas-supply tube 4, 75 which is provided with a controlling valve 5. 6 designates the burner; 7 the mantle; and 8 the globe or shade.

9 designates the ignition tube or opening 80 where the spark meets the gas and ignition takes place.

10 designates a deflector for deflecting the gas upwardly to its opening.

In Figs. 1 to 3, the numeral 11 designates the holder for the piece 12 of pyrophoric alloy, this holder being shown as secured to 85 the ignition tube 9. It has a horizontally extending seat portion 11^a, on which the block 12 is slidably seated, being pressed toward a serrated or roughened abrading wheel 13 by means of a spring 14. The 90 abrading wheel 13 is secured to the upper end of a small shaft 15, which is journaled at its upper portion in the holder 11. 16 is a sleeve which has a sliding telescoping engagement with the shaft 15, and to the lower 95 end of which is hingedly connected the actuating rod 17. The hinge connection between the parts 16 and 17 is preferably effected by a universal joint 18. The member 17 preferably terminates at its lower end in 100 a suitable button or finger piece 19. The sleeve 16 has a longitudinal slot 16^a to receive a pin 16^b on the shaft 15, whereby the sleeve will move freely on the rod, but will be fixed thereto with respect to rotary movement. 20 is an actuating connection between the sleeve 16 and lever arm 21 on the 105 stem of the gas valve 5.

The operation is as follows: When the burner is not lighted, the parts are in the position shown in Fig. 1. To light the burner, the operator takes hold of the finger piece or button 19 with his fingers and pushes upwardly on the rod 17. During this movement, the sleeve 16 slides upwardly on the rod 15 and the gas valve is opened by the movement of the connecting member 20. When the pin 16^b reaches the lower end of the slot 16^a, further upward movement of the actuating rod is stopped. The operator then gives a turning movement to the rod 17, causing the toothed or serrated wheel 13 to exert an abrading action on the pyrophoric alloy, thereby producing a series of hot sparks at the orifice of the ignition tube 9.

In the construction shown in Figs. 4 and 5, the abrading wheel 13^a is connected to a sleeve 30, rotatably mounted in bearings in a bracket 31, connected to the ignition tube 9^a. Mounted for reciprocal and rotary movement within the sleeve 30 is a rod 32. Connected to one end of this rod is the valve-actuating connection 20^a, and hingedly connected to the other end thereof is the actuating rod 17^a. The lower end of the sleeve is provided with a plurality of ratchet teeth 33, and 34 is a pin extending through the rod 32 which is arranged to engage the teeth 33 when the rod is moved upwardly to open the gas valve. The teeth 33 are so shaped that the sleeve 30 and the abrading wheel can only be rotated in one direction by said pin. The operation of this device is the same as that shown in Figs. 1 to 3, except that the abrading can not be operated by the actuating rod until the gas valve has been moved to its full open position by said actuating rod, and at which time the pin 34 will engage the teeth 33.

The pause or interval which naturally occurs on the part of the operator between the end of the reciprocating valve-opening movement and the commencement of the rotary spark-producing movement is just sufficient to insure the gas reaching the ignition opening. This pause the operator is compelled to make in operating the device, and as above stated, it is this feature which broadly characterizes my invention. So long as this feature is present, it will be obvious that the details of the actuating mechanism and of the arrangement of the pyrophoric alloy and of its abrader may be widely varied to suit the particular character of the burner in connection with which the attachment is employed, without departing from the spirit and scope of my invention, as defined in the appended claims.

I claim:

1. The combination with a gas burner having a gas supply valve and an ignition opening, of a lighting device comprising a

spark producing substance, a rotary abrader for said substance, and an actuator connected to the abrader and to the valve, said actuator having a movement in one direction for opening the valve and a subsequent movement in a different direction for operating the abrader; substantially as described. 70

2. In a gas-lighting device, the combination with a supply valve, an ignition opening, and a spark-producing substance, of an abrader for said substance, and an actuating device connected to the abrader and to said valve, said actuating device having a valve-opening movement in one direction and an abrader-operating movement in a different direction, substantially as described. 75 80

3. The combination with a gas burner having a gas-supply valve and an ignition opening, of a lighting device comprising a spark-producing substance, a rotary abrader for said substance, and an actuator connected to the abrader and to the valve, said actuator having a reciprocating movement for opening the valve and a subsequent rotary movement for operating the abrader, substantially as described. 85 90

4. A gas-lighting device, comprising a rotary shaft carrying abrading means, and an actuator having a sliding and also a rotary engagement with said shaft and also having a reciprocating valve-actuating connection, substantially as described. 95

5. A gas-lighting device comprising a rotary abrader, a gas valve, an actuator having a connection with the abrader and the gas valve arranged to reciprocate loosely with respect thereto and means for connecting it thereto with respect to rotary movement, substantially as described. 100 105

6. A gas-lighting attachment, comprising a gas valve, a rotary shaft having abrading means, a member slidably engaging said shaft and the valve, and actuating connections for connecting said member to the shaft, substantially as described. 110

7. A gas-lighting attachment comprising a rotary shaft having abrading means, a sleeve member slidably engaging said shaft, but fixed thereto with respect to rotary movement, and an actuator having a universal joint connection with the sleeve member, substantially as described. 115

8. A gas-lighting attachment comprising a rotary shaft having abrading means, a sleeve member slidably engaging said shaft, but fixed thereto with respect to rotary movement, and an actuator connected to the sleeve member, the sleeve member also having a valve-actuating connection, substantially as described. 120 125

9. A gas lighting attachment, comprising in combination with a gas valve, a rotary sleeve member, a rod member slidably en- 130

gaging said sleeve member, and actuating devices on the sleeve and rod members arranged to be connected when the rod has been moved a predetermined distance, and
5 an actuating connection between one of said members and the gas valve; substantially as described.

In testimony whereof, I have hereunto set my hand.
